SMOKER'S ARTICLE

Eric W. Eweson, New York, N. Y.

Application January 25, 1944, Serial No. 519,673

5 Claims. (Cl. 131—240)

1

This invention relates to a smoker's article, particularly to a tray for holding cigarettes and cigars, and has for an object the provision of improvements in this art.

A particular object is to provide a support adapted to hold a cigarette with a gripping action and which will automatically extinguish it when it has burned back to the gripping elements.

Another object is to provide a holder having a wide horizontal groove for supporting a cigar or cigarette and for directing a cigarette into a gripped or snuffing position in a smaller and deeper groove at the end of the larger groove.

Other objects will be apparent from the following description of an exemplary embodiment, reference being made to the accompanying drawing wherein:

Fig. 1 is a plan view of a smoker's tray embodying the invention;

Fig. 2 is a vertical section taken on the line 2—2 of Fig. 1; and

Fig. 3 is a vertical section and elevation taken on the line 3—3 of Fig. 1.

A plurality of holders 10 may be provided on an ash and stub receiving tray 12 of any suitable material and form. One convenient arrangement is to have a plurality of holders spaced around the rim 14 of the tray. Or the holder, single or duplex, may be provided within the rim 14 where any stubs falling out will drop within the tray and not outside. Or the holders may be provided both inside and on the rim, as shown.

Each holder is formed with a horizontal shelf or ledge 16, preferably grooved on a large radius to take cigars as well as cigarettes. In Fig. 2 a cigar is shown in the grooved ledge of the holder on the left side. Cigars are generally self-extinguishing and do not require special precautions to prevent them from falling off the holder after burning. Cigarettes, however, tend to remain burning even beyond the edge of a support on which they merely rest and this will result in their falling off the support and causing fire or damage to furnishings. Besides, a self-burning or self-smoking cigarette makes an objectionable odor.

For holding and extinguishing cigarettes a second and smaller groove 18 is therefore provided at the bottom of the large groove 16 and at one end thereof. The smaller groove in elevation is formed somewhat in the shape of a broadly truncated V or in the shape of a U with diverging sides and of a size to grip and hold a burning cigarette when placed therein with a slight pressure in a slanting position, as shown on the right side of Fig. 2, or to wedge the burning end of a

2

cigarette which is pushed more or less vertically therein, as shown in the center of Figs. 2 and 3, to snuff it. The bottom of the small groove is open and slightly rounded and sloping on an arc

5 from the bottom of the large groove to the bottom and outer end of the small groove. By continued pushing a cigarette may thus be made to clean the groove after the glow has been extinguished. In any event, the ashes will drop out of the steep-
10 bottomed groove by gravity and any succeeding cigarette will push out the stub of any preceding cigarette which may be wedged in the groove.

It is very easy to introduce a cigarette into the small groove inasmuch as the curved shape
15 of the large groove, intended primarily for cigars, serves as a guide for placing a cigarette into the small groove. When, for instance, a cigarette is lying horizontally in the large groove it needs but a slight pressing touch with a finger and
20 the cigarette will be gripped and held along its length in a sloping position by the small groove, where it will burn for a time, as sometimes desired, but will be extinguished when it has burned back to the gripping edges of the groove. Moreover,
25 when snuffing out a cigarette by placing it vertically in the small groove, one needs but to aim for the large groove, the shape of which guides the cigarette end into the small groove.

As the drawing clearly shows, in this embodiment even the lowermost portion of the small groove is located at a considerable height above the ash receiving bottom of the tray, so high in fact, that when a full length cigarette is wedged centrally in the groove its lower end does not
35 touch the bottom of the tray.

The combination of the two grooves is therefore important. If a cigarette extinguishing device is to be practical it must not only be simple to use and inexpensive to manufacture, but the
40 device must be provided in such a manner as to make a smoker—notably a cigarette smoker—instinctively aware of its availability and purposes the moment he puts his cigarette down on the ash tray. The present invention meets these
45 requirements in a special manner.

While one embodiment of the invention has been specifically described by way of illustration, it is to be understood that there may be various embodiments within the limits of the prior art
50 and the scope of the subjoined claims.

I claim:

1. A smoker's article comprising a support having a horizontal groove of a size to receive and hold a cigar, said support having a small groove at one end of and within the large groove of a

size to grip a cigarette, the small groove in end elevation having the shape of a truncated V, and the large groove having an extended portion which is not touched by the small groove.

2. A smoker's article comprising a support having a horizontal groove of a size to receive and hold a cigar, said support having a small groove at one end of and within the large groove of a size to grip a cigarette, the small groove in end elevation having the shape of a truncated V and having its bottom sloping upwardly in an upwardly concave arc from the outer end to the inner end in the bottom of the large groove, and the large groove having an extended portion which is not touched by the small groove.

3. A smoker's article comprising a tray having a raised edge, said edge having a transverse grooved ledge at the top of a size to hold a cigar

and also a small groove in the inner end only of the large groove, the small groove being of a size to grip a cigarette, being open at the inner end and having an inclined bottom and inner end wall of increasing width from bottom to top.

5. A smoker's article comprising a tray having a raised edge and a raised interior member, said member having a large transverse groove and a smaller truncated V-shaped groove in the bottom of one end only of the large groove opening to the end of the larger groove.

10 6. A smoker's article comprising a tray having a raised edge and a raised interior member, said member having a large transverse groove of a size to hold a cigar and at each end of the large groove having a smaller groove of a size to grip a cigarette.

15 ERIC W. EWESON.
